(57) **CLAIM**

The ornamental design for a hummingbird feeder shade, as
shown and described herein.

DESCRIPTION

FIG. 1 is a perspective view of a hummingbird feeder shade
in accordance with the present invention.

FIG. 2 is a front elevational view of the hummingbird feeder
shade of FIG. 1.

FIG. 3 is a rear elevation view of the hummingbird feeder
shade of FIG. 1.

FIG. 4 is a right side elevational view of the hummingbird
feeder shade of FIG. 1.

FIG. 5 is a top plan view of the hummingbird feeder shade
of FIG. 1; and,

FIG. 6 is a bottom plan view of the hummingbird feeder shade
of FIG. 1.

The broken lines shown in all figures are for illustrative
purposes only and form no part of the claimed design.
